United States Patent Office

Des. 179,409
Patented Dec. 18, 1956

179,409

TOY STRUCTURE

Bruno Prochera, Oyster Bay, N. Y.

Application March 29, 1956, Serial No. 40,830

Term of patent 14 years

(Cl. D34—15)

Fig. 2

Fig. 1

Fig. 4

Fig. 3

Fig. 1 is a front elevational view of a toy structure, showing my design; Fig. 2 is a top plan view of the same; Fig. 3 is a side elevational view of the same looking from the left to the right at Fig. 1; and Fig. 4 is a sectional view of the same taken on line 4—4 of Fig. 1.

I claim:

The ornamental design for a toy structure, as shown.
